UNITED STATES PATENT OFFICE

CLAUDE F. McDONALD AND STANLEY O. McDONALD, OF CAMDEN, OHIO.

RAILROAD-RAIL COUPLING.

1,144,557.

Specification of Letters Patent. Patented June 29, 1915.

Application filed February 8, 1915. Serial No. 6,959.

To all whom it may concern:

Be it known that we, CLAUDE F. McDONALD and STANLEY O. McDONALD, citizens of the United States, residing at Camden, in the county of Preble and State of Ohio, have invented certain new and useful Improvements in Railroad-Rail Couplings, of which the following is a specification.

This invention relates to improvements in railroad rail couplings.

The object of our invention is to provide a strong, durable and boltless union to receive, and hold rigidly together, the confronting ends of two rails. While the coupling is designed to permit the natural expansion and contraction of the rails, it will prevent their vertical or lateral displacement. Furthermore, the coupling is so constructed as not to spread apart, and thereby impair its retaining efficiency, when heavy rolling stock passes over the confronting ends of the rails held thereby.

The preferred form of embodiment of our invention is illustrated in the accompanying drawings, of which—

Figure 1 is a perspective view of the confronting ends of two rails in place within our improved coupling; Fig. 2 is a perspective view of the same, revealing the bottom portions of the coupling and rails. Fig. 3 is a perspective view of the coupling or rail-chair itself. Fig. 4 is a perspective view, partly in section, of the base plate of the coupling. And Fig. 5 is a sectional view through the middle portion of the coupling, showing the gap between the bottom of one of the rails which it receives, and the base plate.

Throughout the specification and drawings, similar reference characters denote corresponding parts.

In a detailed description of our invention, the numeral 1 designates a rail coupling or chair which comprises a base plate 2, upwardly inclined top portions 3—3, and vertical walls 4—4, said plate, top portions and walls being integral with each other and constructed of any metal suitable to impart strength and rigidity to the coupling.

Formed in the lower outer side edges of the said coupling, are notches 5 adapted to receive spikes 6 by means of which it is rigidly secured to ties 7. (See Figs. 1 and 3.)

Referring to Figs. 1, 2 and 5, the numerals

8 and 9 designate two rails whose confronting ends are firmly held together, and in vertical and lateral alignment, by the coupling 1. This coupling is preferably first slipped on the end of one of said rails, so that its vertical walls 4—4 will rigidly embrace the web 10 of the rail, while the base 11 of the latter will be firmly held on the base plate 2 of the coupling by its upwardly inclined top portions 3—3. The coupling is then preferably secured to the ties 7 by the spikes 6, and the confronting end of the other rail slipped into the open end of the coupling, whereupon there is formed a rail chair or union which will firmly support the confronting ends of the rails 8 and 9, and rigidly hold them in vertical and lateral alignment. There are employed in this union no bolts or other connections likely to work loose, the whole coupling unit having marked simplicity and efficiency.

Referring to Figs. 4 and 5, it will be observed that the integral base plate 2 of the coupling 1 has a concave or hollowed-out middle portion 12. The surface of the middle portion of the base plate 2, is made lower than the level of its end surfaces for the following reason. If the two confronting ends of the rails 8 and 9 were to engage the upper surface of the base plate 2 when slightly depressed by heavy rolling stock, there would be sufficient leverage to cause the vertical walls 4—4 to spread sufficiently to release their firm hold upon the web 10 of said rails. With the middle upper surface of the base plate 2 below the confronting ends of said rails—the latter resting upon the two ends of said plate, the confronting rail ends cannot touch the upper surface of the middle portion of said plate, to cause said spreading action of the walls 4—4.

Referring to Figs. 2 and 4, the numeral 13 designates apertures formed in the extreme central portion of the depressed portion 12 of the base plate 2, to permit sand or other foreign substances within said depressed portion to escape; otherwise the confronting rail ends might depress said sand to produce the leverage described.

Our improved coupling for the confronting ends of two rails, though boltless, provides a union that is strong and secure, with no likelihood of the flange portions thereof

spreading apart to release the rails, but on the other hand, firmly holding the latter in vertical and lateral alinement at all times.

Having described our invention, we claim:

- 5 1. A rail coupling comprising a base plate, inwardly and upwardly inclined top portions integral with said base plate, and forming therewith a longitudinal cavity to receive the confronting ends of two rails,
  - 10 and vertical side walls integral with, and extending upwardly from, said top portions, to firmly embrace the web portions of said rails, the middle top surface of said base plate being concave to prevent engagement
  - 15 by the abutting ends of said rails when the latter are depressed, substantially as described.
2. A rail coupling comprising a base plate, inwardly and upwardly inclined top portions integral with said base plate, and

forming therewith a longitudinal cavity to receive the confronting ends of two rails, and vertical side walls integral with and extending upwardly from said top portion, to firmly embrace the web portions of said 25 rails, the middle top surface of said base plate being depressed a sufficient distance, longitudinally and vertically, below the abutting ends of said rails to prevent their engagement with the middle portion of said 30 base plate, substantially as described.

In testimony whereof we have hereunto set our hands this 15th day of April, A. D. 1915.

CLAUDE F. McDONALD.
STANLEY O. McDONALD.
